KEEPER

Frank B. Payne, Oak Park, Ill.

Application June 28, 1946, Serial No. 680,201

3 Claims. (Cl. 292—340)

1

The present invention relates in general to locks and latches, and has more particular reference to lock structures of the sort adapted to be opened, in emergency, without key, from one side of a locked closure member with which the lock structure is associated.

The structure of the present invention is particularly adapted for use in locking doors, windows, or other closure members opening from bathrooms and other closets or compartments, in which the closure member is provided for locking the same for the purpose of assuring privacy, or for other purposes. Particularly where snap, or other self-locking, mechanisms are employed, there is danger of becoming locked within the compartment, in the absence of key means for releasing the lock structure; and the present invention has for an important object the provision of a locking structure having simple, easily operated means for releasing a locked closure member from within a compartment served thereby, in the event that the normal releasing key becomes lost or otherwise unavailable.

Another important object of the invention is to provide lock releasing means of the character mentioned, the operation of which, to release the locked closure member for opening movement, will not damage in any way the lock structure or the structure of the closure member and its co-operating frame.

Another important object is to provide a releasable lock structure, embodying conventional lock bolt means and a keeper for receiving the bolt when in locked position, the keeper being releasably mounted in the structure of the closure means in fashion permitting the same to be released readily from mounted locking position, in response to manipulation of releasing means accessible on one side of the closure structure only.

Another important object is to provide a releasable lock structure, including a keeper member normally mounted in position to lockingly engage a cooperating bolt mechanism of any preferred structure, and adapted to operate for the locking and unlocking of the closure member in conventional fashion, the keeper member being detachable from operating position, so that the closure member may be opened while the bolt mechanism remains lockingly engaged with the keeper member; a further object being to normally anchor the keeper member in operating position by releasable screw threaded means manually operable from the inner side of

2

the closure structure, with which the lock mechanism and releasable keeper plate are operatively associated.

The foregoing and numerous other important objects, advantages, and inherent functions of the invention will become apparent as the same is more fully understood from the following description, which, taken in connection with the accompanying drawings, discloses a preferred embodiment of the invention.

Referring to the drawings:

Fig. 1 is a perspective view of a wall structure having an opening fitted with a closure member, and releasable latch means embodying the present invention;

Fig. 2 is an enlarged sectional view taken substantially along the line 2—2 in Fig. 1; and

Fig. 3 is an enlarged perspective view of a portion of the closure structure shown in Fig. 1, including releasable keeper means embodying the present invention.

To illustrate the invention, the drawings show a wall structure 11 forming a part of a closet, cabinet, compartment, or room, the wall structure having an opening 12 defined by a frame 13. A movable closure member or door 14 is hinged, as at 15, for swinging movement at one edge of the opening 12, whereby the door 14 may be closed in the frame 13, or swung to the open position shown, in order to permit ingress or egress to and from the compartment enclosed by the walls 11. The frame 13, thus, functions as a stationary closure member, in cooperation with the movable closure member 14. A latch or bolt mechanism 16, of any suitable, preferred or conventional form, may be provided, such structure including bolt means 17 adapted to be projected and retracted, as by manually operable means, which conveniently may take the form of a lock actuating key, whereby to lockingly and releasably engage the bolt 17 with cooperating keeper means 18, when the door is in closed position. Obviously, the bolt mechanism may be mounted on either of the closure members 13 and 14, the keeper 18 being mounted on the other.

It will be apparent, of course, that the invention is not necessarily limited to doors, but may be applied to closure structures for windows and other openings. It will be obvious, also, that the invention is not necessarily limited in application to hinged closure members, and may be adapted to arrangements in which the lock structure 16 is mounted in the frame 13, while the keeper means 18 is mounted on the movable clo-

sure member of the combination. As shown, however, the lock structure 16 is applied to the swinging edge of the door 14, in position to lockingly engage the keeper 18 which is mounted on the door frame 13.

The invention contemplates mounting means 19 for securing the keeper 18 normally in operative position on one of the closure members, such as the frame 13, for locking and unlocking co-operation with the bolt of the locking mechanism 16, the mounting means being operable from one side of the closure structure only, to release the keeper 18 from mounted position, in order that the movable closure member may move to uncover the opening 12, while the bolt 17 remains lockingly engaged with the keeper 18. Where the keeper is normally carried by the frame 13, it will, when released, move in engagement with the bolt 17 with the member 14, thereby permitting the same to open. Where, however, the keeper 18 is mounted on the movable closure member, release thereof will allow the closure member to open, leaving the keeper on the stationary closure member 13 in position locked with the bolt 17.

To this end, as shown in the drawings, the keeper 18 may comprise a plate 20 formed with an opening 21 for lockingly receiving the bolt 17, in order to lock the closure member 14 in closed position in the frame 13. The plate 20 is snugly fitted into a seat 22 formed in the closure member on which it is mounted, the plate in the illustrated embodiment being fitted in the seat 22 formed in the frame 13. The plate 20 has a preferably integral extension 23, which projects upon and overlies the side of the frame element facing outwardly of the closure structure, the closure member on which the keeper plate is mounted being preferably formed with a seat 22' for receiving said extension 23, so that all of the exposed surfaces of the plate and its extension may be flush with the surfaces of the closure member on which mounted. The extension 23 carries an anchoring portion 24 which normally extends freely in an opening 25 formed through the closure member on which the keeper is mounted, said anchoring portion preferably comprising an internally screw threaded sleeve member extending in a direction substantially parallel with the plane of the keeper plate 20.

In order to hold the keeper 18 in closure locking position, a threaded stem 26 is provided having a threaded end adapted for engagement with the threaded sleeve 24, said stem extending thence through the closure member and having its remote end projecting at the surface of the closure member remote from the plate projection 23. Said projecting end of the stem is provided with manually operable means, such as the knob 27, whereby the stem 26 may be readily unthreaded and, thus, disconnected from the sleeve 24.

It will be seen that the knob 27 is readily accessible only from one side of the closure structure. As a consequence, when the movable closure member 14 is in locked position in the stationary closure member 13, it may be released for opening movement, in the absence of key means for operating the lock structure 16, only by manipulation of the knob 27 from one side of the closure structure only. By operating the knob 27 to disconnect the stem 26 from the sleeve 24, however, the keeper 18 may be released from the closure member on which mounted. Upon such release of the keeper, the movable closure member may be opened by drawing the keeper from

its seat, the keeper remaining in locked engagement with the bolt. No damage, however, is done either to the closure structure or to the lock mechanism, and the keeper plate thereafter may be immediately remounted in operative position by replacing it on the carrying member of the closure structure and re-threading the stem 26 into place. When in holding position, the stem 26 serves to clamp the keeper 18 in operative position, the extension 23 being clampingly held upon one face of the closure member by action of the stem 26, the knob or head 27 of which clampingly engages the opposite face of the closure member 13.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the form herein disclosed being a preferred embodiment for the purpose of illustrating the invention.

The invention is hereby claimed as follows:

1. A keeper comprising a plate having striker and mounting portions extending substantially at right angles, the one with respect to the other, said striker portion having a latch engaging shoulder formed therein, and said mounting portion having a threaded opening, a threaded anchor stem adapted to engage in said opening in spaced apart, substantially parallel relation with respect to said striker portion, whereby said keeper may be mounted upon a door frame with the said keeper portion lying in the inwardly facing door-jamb surface of the door frame, adjacent and on one side of the door stopping seat of said frame and with the mounting portion extending in the adjacent frame face, on one side thereof, in position to receive the anchor stem in said opening and to support the same in position extending thence through the door frame to the opposite side thereof, and means forming a head on said stem in position to seat on the frame face at said opposite side of the frame to secure the keeper in mounted position on the door-jamb.

2. A keeper as set forth in claim 1, wherein said opening for receiving the anchor stem is formed in a boss on the mounting portion of the plate and extending therefrom in spaced relation with respect to said striker portion.

3. A keeper comprising a plate having striker and mounting portions extending substantially at right angles, the one with respect to the other, said striker portion having a latch engaging shoulder formed therein, means forming a finger-like boss on said mounting portion in position disposed inwardly of and substantially parallel with respect to said striker portion, whereby said keeper may be mounted on a door frame with the said keeper portion lying in the inwardly facing door-jamb surface of the door frame, adjacent and on one side of the door stopping seat of said frame, with the said mounting portion extending in the adjacent frame face, on one side thereof, and with the boss extending in an opening in the frame behind said frame face, said boss being formed with screw threads, a correspondingly threaded anchor stem, formed for threaded engagement with the screw threads of said boss whereby to secure the stem in the boss in position extending thence through the

door frame to the opposite side thereof, and means forming a head on said stem in position to seat on the frame face at said opposite side of the frame to secure the keeper in mounted position on the door-jamb.
